(57) **CLAIM**

The ornamental design for an antenna, as shown and described.

DESCRIPTION

FIG. 1 is a front elevational view of an antenna according to my new design;

FIG. 2 is a top plan view of the antenna shown in FIG. 1; FIG. 3 is a bottom plan view of the antenna shown in FIG. 1;

FIG. 4 is a left side elevational view of the antenna shown in FIG. 1;

FIG. 5 is a right side elevational view of the antenna shown in FIG. 1;

FIG. 6 is a rear elevational view of the antenna shown in FIG. 1;

FIG. 7 is a top plan view of the antenna shown in FIG. 1 with rod antennas retracted;

FIG. 8 is a front perspective view of the antenna shown in FIG. 1;

FIG. 9 is a rear perspective view of the antenna shown in FIG. 1;

FIG. 10 is a front elevational view similar to FIG. 1 of the antenna of FIG. 1 for showing lines cross-sections along which are shown in FIGS. 11 and 12;

FIG. 11 shows only cross-sections of portions of the antenna of FIG. 1 which would be revealed when the antenna is cut along the line 11—11 of FIG. 10; and,

FIG. 12 shows only cross-sections of portions of the antenna of FIG. 1 which would be revealed when the antenna is cut along the line 12—12 of FIG. 10.

The broken away showing of the rod antenna elements indicates that they are of indeterminate length.
